[57] CLAIM

The ornamental design for a paddle, as shown and described.

DESCRIPTION

FIG. 1 is a front elevational view of the paddle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a side elevational view thereof, the broken line showing of a hand and shuttlecock is for illustrative purposes only and forms no part of the claimed design. The broken line showing the shuttlecock in FIGS. 1, 3, 4, 5 and 6 is for illustrative purposes only and forms no part of the claimed design.

FIG. 1
